SPRAYER

Frank H. Maloney, Elmhurst, Long Island, N. Y.,
assignor to Brass Goods Manufacturing Co.,
Brooklyn, N. Y., a corporation of New York

Application November 15, 1939, Serial No. 304,453

5 Claims. (Cl. 299—97)

This invention relates to a sprayer and, particularly, to a device of simplified construction adapted for spraying a liquid upon a window, an automobile wind-shield, clothing, or the like.

The sprayer includes means for delivering liquid to a spraying compartment, a resiliently yieldable diaphragm member for alternately increasing and decreasing the pressure within the said compartment, and a nozzle extending from the diaphragm member. The spraying compartment is continuously in communication with the atmosphere; yet the liquid to be sprayed is introduced into the spraying compartment entirely by suction.

In spraying devices of this general type, including means for drawing liquid by suction into the spraying compartment, it has been customary heretofore to provide a check-valve for closing the nozzle or to use other parts not required in my sprayer, in order to avoid loss of suction within the compartment while liquid is being drawn thereinto.

I have now discovered that, when the orifice in the nozzle is of capillary fineness, the hollow member for delivering liquid to the spraying compartment is relatively large, and the nozzle extends from the spraying compartment in manner shown, then a partial vacuum created momentarily within the spraying compartment draws an adequate amount of liquid thereinto, before the air that enters through the nozzle breaks the partial vacuum. A sprayer based upon this discovery contains relatively few parts and is inexpensive to manufacture. Furthermore, the metal parts of the sprayer may be constructed of sheet metal, in place of machined parts formerly used in sprayers of the same general class.

The invention will be illustrated by description in connection with the attached drawing, to which reference is made.

Fig. 1 is a vertical sectional view of the head of my improved sprayer and a part of a conventional container for a supply of the liquid to be sprayed.

Fig. 2 is a sectional view on line 2—2 of Fig. 1. The spray device illustrated in the drawing comprises a liquid container 1 having a threaded neck 2 and a unitary attachment in the form of a liquid pump. This attachment comprises a cap member 3 including a flat part extending over the open end of the container and a skirt portion formed with threads, so that the cap member may be screwed onto the neck of the container for the liquid.

Mounted upon the cap member 3 is a spraying head including a rigid base member in the form of an annular clamp 4, and an enclosure member resting upon the base member and having at its lower edge a flange portion 5 engaged in a channel formed on the outer edge of the clamp member 4. The said enclosure member defines a spraying compartment with the base member 4.

10 A diaphragm 6 constitutes the major portion of the enclosure member. A relatively stiff portion 7 of the enclosure member is provided with a hole. A nozzle 8 extends through the hole and is provided with a discharge orifice 9 of capillary fineness.

15 The clamp member 4 is formed with a central opening above the open end of the container and with an upstanding flange 10 around the opening. The cap member 3 is also formed with a central opening of the same diameter as the central opening through the member 4.

20 A tubular member 11, formed with an external shoulder 12 near its upper end, passes as an eyehole through the said openings, so that the shoulder rests against and below the cap member 3. The upper end portion 13 of the tubular member 11 is spun over and around the flange 10, to hold the cap member 3 and the clamp member 4 firmly to one another, between the shoulder 12 and the end portion 13 of the tubular member 11.

25 The member 11 is joined to a tubular extension 14 which, in turn, extends below the level of liquid (not shown) in the container 1. The member 11 and extension 14 together constitute a hollow member or line for delivering liquid to the spraying compartment.

30 Suitably, a gasket 15 is disposed between the top of the container 1 and the cap member 3.

35 The tubular member 11 contains a check-valve including ball 16, normally resting upon the seat 17 provided with a circular hole of diameter somewhat smaller than that of the ball, and a perforated stop plate 18 disposed some distance above the ball, for retaining the ball within the tubular member 11 under all circumstances.

40 The cap member 3, in a portion thereof above the opening at the top of the container 1, is provided with an opening 19 considerably larger than the orifice 9. The cap member is provided also with a groove 20, communicating with the opening 19 and extending therefrom between the members 3 and 4, to provide unrestricted communication between the liquid in the container and the atmosphere.

The spraying compartment, on the other hand, is substantially air-tight except for the sole communication through the orifice 9. There is a snug fit of the nozzle 8 within the thickened portion 7 of the enclosure member of the spraying compartment and of flange 5 of the same member in the channel at the periphery of the clamp member 4. Also, the eyelet 11 is tight against flange 10 at the position of entrance of the eyelet into the spraying compartment.

The internal diameters of the liquid delivery line (11 and 14) and of the orifice 9 are so proportioned that the rate of flow of liquid through the said line is large as compared to the inward flow of air through the orifice 9. As a result, the spraying compartment becomes filled with the liquid to a satisfactory level before the partial vacuum is broken by air entering through the orifice.

For best results, the orifice should have an area of opening of the order of 0.00008 to 0.001 square inch. Particularly good results have been obtained when the orifice has a diameter of about 0.021 inch, corresponding roughly to 0.0003 square inch. While the orifice may have various shapes, the orifice should have a resistance to the flow of air therethrough approximately equal to that of a circular hole of the size stated.

While the orifice 9 should be of capillary fineness, the liquid lines 11 and 14 should be large, so as to permit free flow of liquid to the spraying compartment. Thus, the liquid lines should have each a flow area of the order of at least 0.008 square inch. A suitable liquid delivery line, for instance, is rubber hose of three-sixteenth inch internal diameter fitted in conventional manner to the connecting member 11. There is no objection to a very large liquid delivery line, except that when the line becomes over a quarter to half inch in internal diameter, the line may become cumbersome and inconvenient without any offsetting advantage.

The ratio between the areas of openings in the liquid delivery line and the orifice 9 will vary with the consistency of the liquid to be sprayed and the amount of liquid that it is desired to spray with each depression of the diaphragm. For some purposes the ratio of the internal diameter of the liquid supplying line and of the orifice 9 is made so large that liquid is drawn into the spraying compartment at a rate of the order of or even more rapid than the rate at which air is admitted thereto, under the same differential between atmospheric pressure on the liquid in the container and the reduced pressure within the spraying compartment.

In general, the size of opening in the liquid delivery line may be smaller in sprayers for non-viscous liquids, such as wind-shield compositions and perfumes, than for more viscous products such as glycerin. Depending in this manner upon the viscosity of the liquid to be sprayed, the area of opening in the members 11 and 14 for best results should be many times that of the orifice, say, at least about ten times the area of cross section of the orifice.

A convenient method of operating the sprayer is as follows.

The hand is placed around the cap member 3 or upper part of the container 1, with the thumb on the diaphragm 6. The diaphragm is then alternately forced downward and released, so that the pressure in the spraying compartment is first increased and then decreased. When the dia-

phragm has been thus pressed and allowed to recover a number of times, sufficient liquid will have been drawn into the spraying compartment to reach the level of the orifice 9. Continuing the manipulation of the diaphragm then forces a spray of liquid from the orifice, as the diaphragm is depressed, and draws into the spraying compartment additional liquid, as well as air, when the diaphragm is allowed to return to its normal position. The resulting intermittent spray is very satisfactory.

It will be understood that the liquid drawn into the spraying compartment is retained in position for spraying by means such as the ball check-valve described. Metal balls are satisfactory in the valve, particularly when constituted of material that does not corrode in the liquid being sprayed.

The nozzle is in direct and unrestricted communication with the spraying compartment. This is a distinction from certain earlier sprays in which a check-valve was associated with the nozzle, to prevent entrance of air through the nozzle into the spraying compartment during that part of the spraying cycle when the compartment is under a partial vacuum.

In the eyeleted connection of the members 3 and 4, member 3 is free to rotate around the eyelet 11. Or, when the member 3 is screwed on to the container, then the spraying head may be rotated on part 11 as a pivot, without loosening the engagement of the cap 3 on the container.

The enclosure member of the spraying compartment extends on the inside a substantial distance above the level of the orifice in the nozzle. With such a construction, the return of the diaphragm to the normal position, after the release of pressure thereon, draws liquid to a level above the orifice before the pressure of air within the upper part of the enclosing member reaches atmospheric. Advantageously, approximately a third or more of the volume of the spraying compartment is above the level of the orifice in the nozzle and the diaphragm is adapted to be depressed well below the level of the orifice, to expel not only liquid spray but also considerable air from the compartment, before the diaphragm is released.

For the parts described, usual materials of construction may be used. Rubber has been used satisfactorily, as the chief constituent of the enclosure member of the spraying compartment including the diaphragm 6, portion 7, and flange 5. As the diaphragm 6, there has been used to advantage a rather heavy rubber member which is convex upward and constitutes the major part of the generally dome-shaped enclosure over the spraying compartment. For the portion 7 of the enclosure which holds the nozzle, I have used the same material in a somewhat thicker layer or in stiffened form, so as to minimize change of direction of the nozzle as the diaphragm 6 is manipulated. Other resiliently yieldable materials may, of course, be substituted for the rubber as, for example, polymerized chloroprene of rubbery consistency, synthetic rubber, or the like. In any case, usual compounding ingredients may be incorporated.

Cap member 3 and clamp 4 are suitably constructed of sheet metal and the nozzle 8 and eyelet 11 of metal tubing, say, of copper, brass, or plated steel.

The details that have been given are for the purpose of illustration of the invention, not re-

striction. It is intended, therefore, that variations within the spirit of the invention are to be included within the scope of the appended claims.

I claim:

1. A sprayer comprising a spraying head and means for delivering thereto liquid to be sprayed, the spraying head including a rigid base member, a peripheral channel thereon, a resilient member resting at its edge upon the base member and defining therewith the spraying compartment, a flange extending laterally from the said edge of the resilient member and engaged in the said channel, and a nozzle extending through the resilient member.

2. A sprayer for mounting on the neck of a container comprising a cap member of sheet metal having depending means for engaging the container neck and an integral inwardly extending flange, a head comprising a base member of sheet metal resting upon said flange, and a top member engaged by the base member and enclosing a spraying chamber, the top member including a nozzle and a spraying diaphragm forming a wall of the chamber, a tubular member arranged to extend into the liquid in the container, the upper portion of said tubular member being formed of sheet metal and extending through registering openings in the cap member.

flange and the base member, and having a liquid-tight engagement with said base member, the tubular member being provided with means for preventing substantial back-flow of liquid into the container.

3. A sprayer as set forth in claim 2 in which the upper margin of the tubular member is turned outwardly and downwardly into clamping engagement with the upturned central margin of the base member.

4. A sprayer as set forth in claim 2 in which the upper portion of the tubular member includes an integral portion deflected outwardly into engagement with said flange of the cap member, arranged to maintain said base member and cap member in assembled position.

5. A sprayer comprising a spraying head and means for delivering thereto liquid to be sprayed, the spraying head including a rigid base member, a peripheral channel associated therewith, a resilient member resting at its bottom portion upon the base member and defining therewith the spraying compartment, a flange extending laterally from the said bottom portion of the resilient member and engaged in the said channel, and a nozzle extending through the resilient member.
